MOTOR OPERATED SECTIONAL SLIDING DOOR

John P. Reinhardt, Brooklyn, N. Y.

Application March 26, 1949, Serial No. 83,589

14 Claims. (Cl. 160—188)

1

This invention relates to motor operated sectional sliding doors operating in tracks and movable from vertical position closing the door opening to a horizontal position above the door opening and uncovering the same.

An object of this invention is to provide a motor operated door of the character described comprising a motor driven shaft carrying sprocket wheels and chains over the sprocket wheels connected to the lower ends of the door so that when the shaft is rotated in one direction, the door is lifted to slide the sections of the door from vertical portions of the tracks or guides and then around curved upper portions of the guides into horizontal portions of the guides.

Yet another object is to provide in a motor operated door of the character described, spring means to take up slack in the chains when the door is lifted, the spring means being fully compressed at the beginning of the downward movement of the door, and as the sections of the door come into the vertical guide or track, the tension on the chain increases until the tension on the spring means eases up.

Yet a further object of this invention is to provide a strong, rugged and durable motor operated door construction of the character described which may be used for factories and the like, which shall be smooth and positive in operation and practical and efficient to a high degree in use.

Other objects of this invention will in part be obvious and in part hereinafter pointed out.

The invention accordingly consists in the features of construction, combination of elements, and arrangement of parts which will be exemplified in the construction hereinafter described, and of which the scope of invention will be indicated in the following claims.

In the accompanying drawings in which is shown various illustrative embodiments of this invention:

Fig. 1 is a front elevational view of a motor operated door embodying the invention showing the door in full lines partially lifted up, and in dotted lines in the downward position of the door and with parts broken away and in cross-section;

Fig. 2 is a top plan view of the motor controlled chain drive;

Fig. 3 is a cross-sectional view taken on line 3—3 of Fig. 1;

Fig. 4 is a cross-sectional view taken on line 4—4 of Fig. 3;

Fig. 5 is a partially enlarged cross-sectional view taken on line 5—5 of Fig. 3;

2

Fig. 6 is a partially enlarged view illustrating the interconnected sections of the door and the guide track therefor;

Fig. 7 is an enlarged side elevational view of the spring slack take-up means between the uppermost section of the door and the upper end of the chains;

Fig. 8 is a cross-sectional view taken on line 8—8 of Fig. 7;

Fig. 9 is a cross-sectional view taken on line 9—9 of Fig. 7; and

Fig. 10 is a partial view showing the connection between one of the chains and the lower end of the door.

Referring now in detail to the drawing, 10 designates a floor, 11 designates a wall formed with a door opening 12, and 13 designates a ceiling. In the drawing, 14 designates a sectional door for closing the door opening 12. The door 14 is supported by a pair of similar symmetrical or opposed guide tracks 15. Each guide track 15 comprises a vertical portion 16, a curved top portion 17, and rearwardly extending horizontal portion 18. The vertical portions 16 are located on opposite sides of the door opening 12 and inwardly of said door opening.

The lower ends of the tracks 15 are anchored, as at 20 in the floor 10. The tracks are of channel shape cross-section, each comprising a web 21 and flanges 22 extending inwardly from the web 21. The top portions 18 of the track are spaced below the ceiling 13, as shown in Fig. 3 of the drawing. They are further located preferably above the upper end of the door opening 12 so that when the door 14 moves from the vertical portions 16 of the tracks to the horizontal portions 18 of the tracks, the entire door will be disposed wholly above the door opening 12.

The door 14 comprises a plurality of inter-pivoted door sections 25. Each door section 25 comprises a rectangular section frame 26 which may carry a window or panel 27. The lower side 28 of each frame section 26 contacts the upper side 29 of each adjacent section. The parts 28 and 29 may be formed with overlapping flanges 28a, 29a, as shown in Fig. 6 of the drawing. Of course, the upper side of the topmost section 25 does not have such a flange, and the same is true of the lowermost section. Attached to the ends 30 of the lower sides 28 of the sections 25 are downwardly and inwardly inclined brackets 30; and extending upwardly and attached to the ends of the top portions 29 of the sections, are upwardly and inwardly extending brackets 31. The brackets 30 and 31 are interpivoted by pivot pins

32 which serve as shafts for carrying the rollers 33 which roll within the channel tracks 15. At 33 which roll within the channel tracks 15. At the lower ends of the lowermost section 25 are downwardly and inwardly extending brackets 34 carrying similar rollers 35 received from within the tracks. Fixed to the upper portions of the topmost section are inwardly extending brackets 37 carrying rollers 38 received from within said tracks.

When the door is lifted in the manner hereinafter to be described, as the rollers 33 move from the vertical track sections 16 around the curved track sections 17, the sections 25 will swing relatively to one another about the pivot shafts 32. Thus adjacent portions of adjacent sections will separate as said sections move through the curved portions 17 of the tracks, and then said adjacent portions of said adjacent sections will again move toward each other as said sections move either into the horizontal track parts 18 or into the vertical track parts 16. It will be noted that the door 14 when in vertical or down position is located just rearwardly of the door opening 12 and between the wall 11 and the vertical portions 16 of the tracks 15. It will also be noted that the horizontal portions 18 of the tracks are of sufficient length so that the entire door may be raised and moved into horizontal position, as shown in Fig. 3 of the drawing.

Means is provided for lifting and lowering the door 15. To this end, there is fixed to the underside of the ceiling 13, brackets 40 carrying bearings 41 supporting for rotation a horizontal shaft 42. The shaft 42 is located above the track portions 18 and just in back of the wall 11. To one end of the shaft 42 is fixed a worm wheel 43. Rotatably mounted on a bracket 44 supported in any suitable manner, is a worm 45 meshing with the worm wheel 43. The axis of the worm 45 is perpendicular to the axis of the shaft 42. The worm 45 is supported on a horizontal shaft 46. Fixed to said shaft for rotation with the worm 45 is a gear 47.

Supported on a fixed bracket 48 is an electric motor 49. Fixed to the motor shaft 50 is a pinion 51 meshing with the gear 47. It will now be understood that when the motor is energized the shaft 42 will be rotated. The motor is preferably a reversible motor so that the shaft 42 may be rotated in either direction. Fixed to the shaft 42 are a pair of sprocket wheels 53 disposed substantially in the plane of the tracks 15.

Attached to the ceiling 13 are brackets 55 rotatably supporting a horizontal shaft 56 parallel to shaft 42 and disposed rearwardly therewith and at a somewhat lower level. Fixed to the shaft 56 for rotation therewith are a pair of sprocket wheels 57 aligned with the sprocket wheels 53. Extending over the sprocket wheels 53 and under the sprocket wheels 57 are a pair of sprocket chains 60. The lower ends of the sprocket chains 60 are fixed to the lower ends of the lowermost door section, as shown in Figs. 1 and 10 of the drawing. There may be attached to the lowermost door section at the ends thereof and adjacent the lower edges thereof, suitable brackets 62 carrying pins 63 to which the lower ends of the chains 60 are attached.

When the shaft 42 is rotated in a clockwise direction, looking at Fig. 3 of the drawing, the chains will pull up the door and slide the sections from vertical to horizontal position, or in

other words, from track sections 16 around track sections 17 and on to track sections 18.

Means is provided to connect the upper end of the door to the rear ends of the chains 60. To this end, there is slidably mounted on and between the horizontal portions 18 of the tracks, a carriage 65. The carriage 65 comprises a pair of angular members 66. Each member 66 has a horizontal rearwardly extending portion 67 and a vertical upwardly extending portion 68. The upper ends of the portion 68 are interconnected by a horizontal rod 69. The front and rear ends of portions 67 are interconnected by horizontal rods 70 and 71 respectively. The angular members 66 are located inside of the tracks. Mounted for rotation on the ends of the shaft 70 and 71 are rollers 72 and 73 which may rotate within the horizontal portions 18 of the tracks 15.

The rear ends of the chains 60 are fixed to the outer ends of the transverse shaft 69. On the shaft 71 is a sleeve 75 fixed to the angular member 66. Fixed to the ends of the sleeves 75 are lugs 76. The lugs 76 are formed with through openings 77 for the purpose hereinafter appearing. Mounted for rotation in the tracks 15 are rollers 77 supported on shafts 78. The rollers 77 are located between the rollers 73 and the front wall 11. On shafts 78 are sleeves 79. Fixed to the sleeves are upstanding lugs 80 parallel to the lugs 76. The lugs 80 are formed with through openings 81 aligned with the opening 76. Pivotally interconnecting the shaft 78 with the pivot shafts 84 in the rollers 38 are links 85. Thus, the shafts 84 supported by the brackets 37 of the topmost door section 25 are connected by links 85 to the shafts 78 which carry the rollers 77 and which support the upstanding lugs 80. Extending through the aligned openings 77 and 81 of the lugs 76 and 80 and adjacent each track is a horizontal rod 88. Screwed to the ends of the rods 88 are heads 89. Any suitable heads may be provided for the ends of the rods 88. Surrounding each rod 88 and interposed between the lugs 76 and 80 is a coil compression spring 90.

The operation of the device will now be described. As the motor operates to rotate the shaft 42 in a clockwise direction, looking at Fig. 5 of the drawing, the chains 60 will lift the door 14 and the springs 90 will take up the slack in the rear end of the chains. The sprocket wheels 57 serve as idlers. Thus, the door may be lifted from the full to the dotted line shown in the drawing, the door moving from the vertical portions of the tracks to the horizontal portion of said tracks, and as the door sections swing around the portions 17, the springs 90 serve to take up the slack in the chain. When the motor is reversed to lower the door, the spring 90 is first fully compressed as the chain 60 pulls the carriage 65 to the left, but as the door progresses downwardly into the vertical portions of the bracket 16, the tension on the chain increases until the tension on the springs 90 eases up.

Any suitable switch means may be used for stopping the operation of the motor in the fully closed and the fully open position of the door.

It will thus be seen that there is provided a device in which the several objects of this invention are achieved, and which is well adapted to meet the conditions of practical use.

As various possible embodiments might be made of the above invention, and as various changes might be made in the embodiment above

set forth, it is to be understood that all matter herein set forth or shown in the accompanying drawing is to be interpreted as illustrative and not in a limiting sense.

Having thus described my invention, I claim as new and desire to secure by Letters Patent:

1. In combination with a pair of aligned tracks having vertical portions, curved portions at the upper ends of the vertical portions and horizontal portions extending from said curved portions, a sectional door comprising interpivoted sections, rollers on said sections disposed within said tracks, a horizontal shaft above said track, sprocket wheels on said shaft, motor means for rotating said shaft, inextensible chains on said sprocket wheels respectively having their lower ends connected to the lower end of the door, a carriage slidably mounted on and between the horizontal portions of said tracks in spaced relation to the upper end of the door, the rear ends of said chains being connected to said carriage, and means, including spring means interposed between the upper end of the door and said carriage, to urge the carriage away from the door and to take up slack in said chain.

2. In combination with a pair of aligned symmetrical tracks having vertical upwardly extending portions and rearwardly extending horizontal portions and curved portions interconnecting said vertical and horizontal portions, a sectional door comprising a plurality of sections, brackets fixed to adjacent portions of said sections, interpivot means to connect said brackets, rollers on said interpivot means received within said tracks, a horizontal shaft mounted for rotation, sprocket wheels on said shaft, reversible motor means for rotating said shaft in opposite directions, a second shaft parallel to the first shaft, idler sprocket wheels on said second shaft, inextensible chains connected at their lower ends to the lowermost section of the door and passing over the first mentioned sprocket wheels and under the second mentioned sprocket wheels, a carriage slidably mounted on and between said horizontal portions of said tracks and connected to the rear ends of said chains, said carriage being spaced rearwardly of the uppermost section of the door, a pair of rollers mounted on said tracks, links connecting said pair of rollers to the uppermost section of said door, and means including spring means interposed between said pair of rollers and said carriage to urge the carriage away from the door and to take up slack in the chains as the door is lifted.

3. In combination with a door opening, and a pair of tracks having vertical portions at opposite sides of the door opening and inwardly extending horizontal portions above the door opening connected to the vertical portions of the tracks by upwardly and inwardly curved track portions, a sectional door comprising a plurality of door sections in tandem, brackets at the adjacent portions of adjacent sections, pivot pins interpivoting said brackets, rollers on said pivot pins received within said tracks, brackets at the lower ends of the lowermost section and provided with pins carrying rollers received in said tracks, brackets at the upper ends of the uppermost section provided with pins carrying rollers received within said tracks, rollers in the horizontal portions of said tracks, a transverse shaft to support said rollers, links interconnecting the last mentioned pins with said transverse shaft, lugs fixed with respect to said transverse shaft, and extending upwardly therefrom and formed

50

55

60

65

75

with openings, a carriage slidably mounted on and between said horizontal portions of said tracks, lugs on said carriage formed with openings aligned with the openings in the first mentioned lugs respectively, a rod slidably passing through each pair of aligned openings, heads at the ends of each of said rods, a coil compression spring on each of said rods and between said lugs which have the opening through which the rod passes, flexible inextensible pull means having opposite ends connected to the lowermost section of the door and to the carriage, and drive means in driving engagement with the pull means intermediate the ends of said pull means.

4. In combination, a door comprising a plurality of interpivoted sections, guide tracks on which said door travels, a carriage mounted on said tracks for movement thereon and being spaced from the upper end of the door, flexible inextensible pull means connecting the lower end of the door to said carriage, spring take up means interposed between the upper end of said door and carriage to move the carriage away from the upper end of the door and to take up slack in said pull means, and means to move said pull means in opposite directions, said spring take up means comprising stops movable with said carriage and with the uppermost section of said door respectively, a coil compression spring between said stops and means slidable relative to at least one of said stops to support said spring.

5. In combination, a door comprising a plurality of interpivoted sections, guide tracks on which said door travels, a carriage mounted on said tracks for movement thereon, said carriage being spaced from the upper end of the door, an electric reversible motor, a shaft, drive means connecting said motor with said shaft, a pair of sprocket wheels fixed to said shaft, and inextensible sprocket chains meshing with said wheels and each connected at one end to the lowermost section of the door, and at the other end to said carriage, stops movable with said carriage and with the uppermost section of said door respectively, a coil compression spring between said stops to push the carriage away from the door and take up slack in the chains, and means slidable relative to at least one of said stops to support said spring.

6. In combination with a pair of aligned tracks having vertical portions, rearwardly curved portions at the upper ends of the vertical portions and horizontal portions extending from said curved portions, a sectional door comprising interpivoted sections, rollers on said section disposed within said tracks, a horizontal shaft above said track, sprocket wheels on said shaft, motor means for rotating said shaft, chains on said sprocket wheels connected to the lower end of the door, a carriage slidably mounted on and between the horizontal portions of said tracks, the rear ends of said chains being connected to said carriage and spring means to take up slack in said chains, interposed between the upper end of the door with said carriage, said carriage comprising a pair of aligned angle brackets each having a horizontal portion and a vertical portion, a pair of horizontally aligned parallel shafts interconnecting the horizontal portion of said brackets, a horizontal shaft interconnecting the vertical portions of said brackets, rollers on said pair of brackets received in said tracks.

7. In combination, a pair of aligned guide tracks having vertical portions, curved portions at the upper ends of said vertical portions, and

horizontal portions extending from said curved portions, said tracks comprising channels opening inwardly, a door comprising a plurality of sections having edge to edge contact, means to interpivot adjacent sections about pivots offset from the plane of the door, rollers on said pivots received in said tracks, a shaft carrying rollers received in the horizontal portion of the tracks and connected by links to the uppermost section, a carriage carrying rollers received in the horizontal portions of said tracks, take up springs interposed between said carriage and shaft, a drive shaft, sprocket wheels thereon, sprocket chains meshing with said sprocket wheels, one end of each chain being attached to said carriage, and the other end being attached to the lowermost section of said door, a reversible electric motor and means to connect said motor for rotating said sprocket wheels.

8. In combination, a pair of aligned guide tracks having vertical portions, curved portions at the upper ends of said vertical portions, and horizontal portions extending from said curved portions, said tracks comprising channels opening inwardly, a door comprising a plurality of sections having edge to edge contact, means to interpivot adjacent sections about pivots offset from the plane of the door, rollers on said pivots received in said tracks, a shaft carrying rollers received in the horizontal portion of the tracks and connected by links to the uppermost section, a carriage carrying rollers received in the horizontal portions of said tracks, take up springs interposed between said carriage and shaft, a drive shaft, sprocket wheels thereon, sprocket chains meshing with said sprocket wheels, one end of each chain being attached to said carriage, and the other end being attached to the lowermost section of said door, a reversible electric motor and means including a worm and worm gear to connect said motor for rotating said sprocket wheels, and idler sprocket wheels meshing with said chains.

9. In combination, guide tracks for a sectional door including a vertical portion, an upwardly and rearwardly curved portion extending from the upper end of the vertical portion and a horizontal rearwardly extending portion extending from said curved portion, a sectional door comprising door sections adapted to be located in a plane in front of the vertical portion of the track, brackets extending rearwardly from said sections, means to interpivot the brackets at adjacent ends to adjacent sections, rollers on the interpivot means located within said track, rotary sprocket wheels above the vertical portion of the track, reversible motor means to rotate said sprocket wheels, in opposite directions, sprocket chains engaging said sprocket wheels, said chains having vertical portions disposed in front of the vertical portions of the track and connected at their lower ends of the lowermost section to the door and disposed in the plane of said sections when the door is in its down position, a carriage slidably mounted on the horizontal portion of the track and being spaced rearwardly of the upper end of the door, means to connect the opposite ends of said chains to said carriage, and spring compression means interposed between the uppermost section and the carriage to push the carriage away from said uppermost section and to take up slack in said chains and whereby when the door is in its down position and the motor is operated in one direction the chains will pull the door upwardly from

its lower end so that said section will turn from the vertical portion of the track around the curved portion of the track into the horizontal portion of the track, and when the motor is reversed said opposite ends of the chain will pull the carriage forwardly to compress the spring means and push the door forwardly of the horizontal track and around the curved portion of the track into the vertical portion of the track.

10. In combination, guide tracks for a sectional door including a vertical portion, an upwardly and rearwardly curved portion extending from the upper end of the vertical portion and a horizontal rearwardly extending portion extending from said curved portion, a sectional door comprising door sections adapted to be located in a plane in front of the vertical portion of the track, brackets extending rearwardly from said sections, means to interpivot the brackets at adjacent ends to adjacent sections, rollers on the interpivot means located within said track, rotary sprocket wheels above the vertical portion of the track, reversible motor means to rotate said sprocket wheels, in opposite directions, sprocket chains engaging said sprocket wheels, said chains having vertical portions disposed in front of the vertical portions of the track and connected at their lower ends of the lowermost section to the door and disposed in the plane of said sections when the door is in its down position, a carriage slidably mounted on the horizontal portion of the track and being spaced rearwardly of the uppermost section of the door, means to connect the opposite ends of said chains to said carriage, and spring compression means interposed between the uppermost section and the carriage to push the carriage away from the door and take up slack in the chains, and whereby when the door is in its down position and the motor is operated in one direction the chains will pull the door upwardly from its lower end so that said section will turn from the vertical portion of the track around the curved portion of the track into the horizontal portion of the track, and when the motor is reversed said opposite ends of the chain will pull the carriage forwardly to compress the spring means and push the door forwardly of the horizontal track and around the curved portion of the track into the vertical portion of the track, and worm and worm gear means interposed between the motor and the sprocket wheels.

11. In combination, a door comprising a plurality of interpivoted sections, guide tracks on which said door travels, including an upwardly extending portion and a rearwardly extending portion, and a curved portion connecting the rearwardly extending portion with the upper end of the upwardly extending portion, a carriage on the rearwardly extending portion of said tracks and spaced rearwardly of the upper end of the door, springs interconnecting said carriage with the uppermost section of the door and urging the carriage away from the door, a sprocket wheel mounted for rotation above the upwardly extending portion of the track, a sprocket chain engaging said wheel and connected at its lower end to the lowermost section of the door and at its opposite end to the carriage whereby the slack in the chain is taken up by said springs, an electric motor and drive means connecting the electric motor with said sprocket wheel.

12. In combination, a door comprising a plurality of interpivoted sections, guide tracks on

which said door travels, including an upwardly extending portion and a rearwardly extending portion, and a curved portion connecting the rearwardly extending portion with the upper end of the upwardly extending portion, a carriage on the rearwardly extending portion of said tracks and spaced rearwardly of the upper end of the door, springs interconnecting said carriage with the uppermost section of the door and urging the carriage away from the door, a sprocket wheel mounted for rotation above the upwardly extending portion of the track, a sprocket chain engaging said wheel and connected at its lower end to the lowermost section of the door and at its opposite end to the carriage whereby the slack in the chain is taken up by said springs, an electric motor and drive means connecting the electric motor with said sprocket wheel, said drive means including a worm and worm wheel.

13. In combination, a door comprising a plurality of interpivoted sections, guide tracks on which said door travels, said guide tracks having vertical and horizontal portions and a curved interconnecting portion, a carriage slidably mounted on the horizontal portion of said tracks for movement thereon and being spaced horizontally from the upper end of the door, flexible pull means connecting the lower end of the door to said carriage, means including spring means interposed between the upper end of the door and the carriage, to move the carriage away from the door and to take up slack in said pull means, and means to move said pull means in opposite directions.

14. In combination, a door comprising a plurality of interpivoted sections, guide tracks on which said door travels, a carriage mounted on

said tracks for movement thereon, an electric reversible motor, a shaft, drive means connecting said motor with said shaft, a pair of sprocket wheels fixed to said shaft, sprocket chains meshing with said wheels and each connected at one end to the lowermost section of the door, and at the other end to said carriage, said carriage being spaced from the upper end of the door and means including compression spring means interposed between said carriage and door to take up slack in said sprocket chains, and to push the carriage away from the door.

JOHN P. REINHARDT.
